[57] CLAIM

The ornamental design for a telephone terminal block
or similar article, substantially as shown and described.

DESCRIPTION

FIG. 1 is a front perspective view of a telephone terminal
block or similar article showing my new design;

FIG. 2 is a similar perspective view thereof showing a
cover element thereof in closed condition;

FIG. 3 is a front elevational view thereof showing the
device in the condition shown in FIG. 1;

FIG. 4 is a front elevational view thereof showing the
device in the condition shown in FIG. 2;

FIG. 5 is a side elevational view thereof in partially
opened condition, the opposite side being symmetrical;

FIG. 6 is a side elevational view thereof showing the
device in closed condition;

FIG. 7 is a top plan view thereof showing the device in
opened condition;

FIG. 8 is a top plan view thereof showing the device in
closed condition;

FIG. 9 is a bottom plan view thereof showing the device
in opened condition;

FIG. 10 is a bottom plan view showing the device in
closed condition; and

FIG. 11 is a rear elevational view thereof.

FIG. 1.

FIG. 2.

FIG. 3.

FIG. 4.

FIG. 5.

FIG. 6.

FIG. 7.

FIG. 8.

FIG. 9.

FIG. 10.
